UNITED STATES PATENT OFFICE.

E. A. ROBINSON, OF WATERBURY, CONNECTICUT, ASSIGNOR TO THE UNITED STATES BUTTON COMPANY, OF SAME PLACE.

IMPROVEMENT IN BUTTONS.

Specification forming part of Letters Patent No. **57,260**, dated August 14, 1866.

To all whom it may concern:

Be it known that I, E. A. ROBINSON, of Waterbury, New Haven county, State of Connecticut, have invented a new and useful Improvement in the Manufacture of Buttons; and I do hereby declare that the following is a full, clear, and exact description thereof, which will enable others skilled in the art to make and use the same, reference being had to the accompanying drawings, forming part of this specification.

The present invention relates to the mode of securing the eye or loop of the button, by which it is fastened to the garment, to its mold; and it consists in the use of a metallic or other suitable plate made of a corresponding diameter, or nearly so, to that of the mold, the center of which plate is broken out, forming a ragged edge, flange, or lip, and the plate by this flange driven into the center opening through the mold, in which the eye or loop is first placed, thereby tightly and firmly securing such loop therein, from which it can not possibly be withdrawn by the ordinary wear or strain upon the button when in use.

In accompanying plate of drawings my improvements in the manufacture of buttons are illustrated, Figure 1 being an edge view of the mold with the loop or eye and the metallic plate used for fastening the loop in the mold placed in proper position for being driven; Fig. 2, a view of the under side of the metallic plate, showing its center flange or ragged edge; Fig. 3, a view of the under or rear side of the mold; and Fig. 4, an edge view of the mold with the loop secured to it by driving in the metallic plate.

Similar letters of reference indicate like parts.

A in the drawings represents the mold of the button, having an opening, *a*, made in its

center through its entire thickness, in which is placed the ends of the loop B, so as to project from the rear side or face C of the button, the button by this loop being fastened to the garment desired; D, a metallic plate made of a diameter corresponding to that of the mold A, or nearly so, the central portion of which plate is broken out in any proper manner to form a ragged or broken edge or flange or lip, E, which edge, to secure the loop in the mold, is placed in the opening *a* thereof made in the center of the mold to receive the loop, and then driven therein in any proper manner, bringing the plate down and upon the mold and securely binding, fastening, and holding the loop to and in the mold, as is obvious, without further explanation, and, furthermore, with so much strength that no ordinary wear or strain upon the button can loosen it.

In lieu of securing the loop to the mold, as above explained, the ragged side of the blank or metallic plate D may be placed uppermost upon the mold, when, then passing the loop-cord from the ragged side of the blank through both the blank and mold, it can be securely fastened in place and to the button, as is apparent.

I claim as new and desire to secure by Letters Patent—

A button having the loop secured to and in the mold by means of a metallic plate or blank, D, having a ragged edge or lip, E, substantially in the manner described.

The above specification of my invention signed by me this 8th day of March, 1866.

E. A. ROBINSON.
